2 Claims. (Cl. 102—25)

The present invention relates to improvements in or relating to air blasting devices of the type wherein a gas compressed to a very high pressure enclosed in a container is abruptly expanded by the rupture of a plate or actuation of a piston under the effect of the gas pressure, and injected through vents into the rock mass to be blasted or shattered.

More specifically, the invention provides improvements in devices for introducing compressed gas into the said container.

The invention applies to the method of introducing high-pressure gas, which is generally compressed air, into the container which is closed by the device adapted to yield and be displaced under the action of the pressure.

It is known that, in the aforesaid devices, the compressed gas is introduced into the container through a tube extending to the neighbourhood of the yieldable and/or movable device, so as to provide a cooling action.

Numerous tests carried out by the applicant have shown that this cooling device was not sufficient to prevent certain occurrences due to the entrainment of lubricating oil from the compressor into the container of the blasting device. In spite of very comprehensive rules for the use of the device, sufficient precautions are not always taken to prevent oil from being so entrained. Repeated tests have shown that the entrainment of oil could entail risk of explosion in the container of the blasting device at the time of its being filled.

It has been shown by other tests carried out by the applicant that, by judiciously piercing the compressed-gas feeding tube, the danger of a sudden ignition of oil in the container of the blasting device when being filled could be reduced and even completely eliminated.

The disclosure of some of the aforesaid devices points out that the compressed-air supply tube can be provided with apertures for discharging a portion of the air at other points where it is desired to produce a cooling effect. But tests by the applicant have shown that the number, the position and the cross-sectional area of the apertures are far from being unimportant if any risk of oil ignition is to be obviated.

It is possible that elimination of the danger of oil ignition is connected to a suitable distribution of the cooling effect due to the mixing of the fluids, but nothing can be held to be certain in this respect. Whatever be the correct explanation and without being able to prove any particular one, it has been shown by repeated tests that suppression of the danger of oil ignition can only be achieved by as regular as possible a distribution and as regular as possible a mixing of the fluid introduced into the container, with a minimum of four apertures. Under the most severe conditions, a complete effect is achieved with a minimum of eight judiciously placed apertures. In practice, it seems that the best result would be obtained by arranging the orifices and selecting their cross-sections such as to effect an equalisation of pressure throughout said container at all times while filling the container. The physical reality is perhaps different, but nevertheless a new effect can thus be obtained.

2

The invention is characterised in that, in an air-blasting device wherein the blast is effected by a sudden expansion due to the provision of means yieldable and/or movable under pressure, the tube for the introduction of the compressed gas having a length equal to or greater than two-thirds of the length of the container, has a minimum of four lateral apertures.

In accordance with another feature of the invention, the cross-section and the position of these apertures are so related that the mass of fluid introduced per unit volume of the container is substantially constant at any given moment over the entire length of the container.

In accordance with a preferred embodiment, the length of the compressed gas supply tube is at least equal to four-fifths of the length of the container.

In accordance with a further feature, the lateral apertures are of increasing cross-sectional area commencing with those nearest to the tube inlet until those nearest to the extremity of the tube in the case of a cylindrical container.

In accordance with a still further feature, the spacing of the lateral apertures decreases from the inlet to the extremity of the tube.

According to another feature, the orifices are arranged in one or more helices.

In accordance with a preferred embodiment, the compressed gas supply tube comprises a minimum of eight lateral openings.

Other features and advantages of the invention will become clear on reading the following description with reference to the accompanying drawing, in which:

FIGURE 1 shows diagrammatically the tube test arrangement;

FIGURE 2 shows diagrammatically a firing container provided with a gas input tube having four orifices formed therein; and

FIGURES 3A-3B and 4 show, diagrammatically, modified embodiments of compressed gas input tubes in accordance with the invention.

Tests have been carried out under firing conditions in which the danger of oil explosion is maximum.

An oil reservoir 1 having a capacity of a few hundred cubic centimeters immediately follows the firing valve 2 (compressed air inlet valve). A pipe 3 of as small a length as possible (10 m.) connects the unit comprised by the firing valve 2 and the oil reservoir 1 with the container 4 provided with a plate 7. The firing containers under test are cylindrical and have an internal diameter of 63.5 mm.

The compressed air supply tubes 5 are made of copper, have an internal diameter of 4.5 mm. and an external diameter of 9.5 mm. They penetrate into the container 4 provided with a coupling 6.

The tube diagrammatically illustrated in FIGURE 2 is a firing container 4 provided or not with a compressed gas supply tube 5 penetrating into the tube 4 from a coupling 6. As in the case of FIGURE 1, a plate (not shown) closes the firing container; this plate yields under a given pressure and releases the gas into the rock mass to be blasted or shattered through vents 8 (FIGURE 1). This tube has two holes 9, which are preferably diametrically opposed, have a diameter of 1.3 mm., are located in the coupling, and, if desired, have two further holes 9 (which are also preferably diametrically opposed) located at a distance d from this coupling. Different types of tubes have been tested having the following characteristics (the references used in the following table as well as in those further on are as given in general in FIGURE 1).

Table I

Type of tube (figure 2)	Overall length of the firing tube, mm.	Length of container, mm.	Length of the compressed air supply tube, mm.	Distance of the 2 additional orifices from the coupling, mm.	Diameter of the additional orifices, mm.
	a	b	c	d	e
A	1,700	1,510	1,260	—	—
B	1,700	1,510	0	—	—
C	2,650	2,460	2,240	—	—
D	2,650	2,460	2,240	650	2
E	1,700	1,510	1,290	650	2.5

The combustible oils used for the tests were a commercial lubricating oil and a commercial gas oil. Under these test conditions, the commercial gas oil is distinctly more inflammable than the commercial lubricating oil.

For a better understanding of the results, it is to be further pointed out that the risk of air-oil explosion inside the firing container increases when the mean pressure of the compressed air which causes the rupture of the plate plugging the container increases. This effect has been demonstrated by repeated tests.

Table III gives the results obtained for firing tubes of two lengths (170 cm. and 265 cm.) with or without perforated inlet tubes of the types defined in Tables I and II.

Table III

Test No.	Type of combustible oil	Type of tube	Length of compressed air supply tube, mm.	Amount of oil, c.c.	Mean rupture pressure of plate 7, kg./sq. cm.	Frequency of explosion in the container during firing
1	Commercial Lubricating Oil	A	1,260	50	408	4/5
2	do	B	0	50	405	3/5
3	Gas oil	D	2,240	100	600	3/7
4	do	E	1,290	100	600	0/10
5	Commercial Lubricating Oil	F	1,260	50	405	0/10
6	do	F	1,260	100	405	0/10
7	do	F	1,260	100	780	0/10
8	Gas oil	F	1,260	100	390	0/10
9	do	F	1,260	100	780	0/10
10	do	C	2,240	100	390	5/5
11	do	G	2,240	100	600	0/10
12	do	G	1,260	100	600	1/1
13	do	G	1,400	100	600	1/1
14	do	G	1,610	100	600	0/10
15	do	G	1,750	100	600	0/10
16	do	Fig. 4	2,240	100	650	0/10

On the other hand, firing containers in accordance with the invention whose compressed air input tubes are provided with orifices 9, the first two of which are located adjacent the inlet coupling or in this coupling (FIGURES 3A and 3B) and the others as shown in Table II, have also been tested.

Comparison between tests Nos. 1, 2, 3 and 10 on the one hand, and tests Nos. 4, 5, 6, 7, 8, 9, 11 and 16 on the other hand, shows that the danger of oil-air explosion is greatly reduced by the use of an inlet tube in accordance with the invention. Moreover, tests Nos. 12, 13, 14 and 15 show that

Table II

Type of tube (figures 3A and 3B)	Overall length of the firing tube, mm.	Length of container, mm.	Length of the compressed air supply tube, mm.	Total number of orifices	Distances between 2 orifices (other than the first two), mm.	Successive diameters of orifices from the first two to the extremity, mm.
	a	b	c	e		
F	1,700	1,510	1,260	8	180	1.5-1.5-2 2.5-3-3.5 4
G	2,650	2,460	(1)	8	1/4 c	1.3-1.5-2 2.5-3-3.5 4

¹ See Table III.

In the tubes F and G, the orifices are thus arranged in the following manner:

The first two orifices are of identical diameter, are disposed either in the coupling 6 or a few centimeters from this coupling and are diametrically opposed in the tube. Those following are at distances and have diameters as shown in Table II. They are arranged helically so that two successive orifices are located on generatrices of the tube at 90° to each other.

In accordance with the alternative embodiment shown in FIGURE 4, the orifice 9 have the same diameter (1.5 mm.), the distance between two successive orifices decreasing from the first two which are adjacent the coupling 6 up to the extremity of the tube. Thus, advantageously:

$$f_1 = \frac{15}{45}c; f_2 = \frac{10}{45}c; f_3 = \frac{7}{45}c; f_4 = \frac{5}{45}c; f_5 = \frac{3}{45}c; f_6 = \frac{2}{45}c$$

there is a minimum length for the tube having apertures in order to preclude oil-air explosions in the firing container.

Experience has shown that, in using this type of equipment, it may happen that the compressed gas supply tube becomes twisted or spiraled. Tests carried out by the applicant have shown that, beyond a certain length of the apertured tube, spiralling due to compressed air has no effect on safety. This minimum length is four-fifths of the length of the container.

The above disclosure relates to tests carried out with containers of the type provided with a plate. However, the results may be applied to all kinds of firing containers operated by the expansion of a compressed gas.

Although the present invention has been described in conjunction with preferred embodiments, it is to be understood that modifications and variations may be resorted to without departing from the spirit and scope of the in-

vention, as those skilled in the art will readily understand.

Such modifications and variations are considered to be within the purview and scope of the invention and appended claims.

I claim:

1. An air blasting device comprising an elongate container adapted to receive gas under pressure and having vents therein, a vent plugging means in said container adapted to yield to uncover said vents, and a tube for introducing compressed gas into said container, said tube extending longitudinally and into one end of said container and having the end thereof in the container open, said tube having a length in the container equal to at least two-thirds of the length of the container and at least four orifice means in the wall of said tube communicating 15 the interior of the tube with the container, said orifice means being along substantially the entire length of said tube for introducing into said container along the length thereof masses of compressed gas which are substantially equal to each other, whereby to effect equal increase of 20 pressure throughout the length of said container during the filling thereof.

2. An air blasting device comprising an elongate container adapted to receive gas under pressure and having vents therein, a vent plugging means in said container adapted to yield to uncover said vents, and a tube for introducing compressed gas into said container, said tube extending longitudinally and into one end of said con- 25

tainer and having the end thereof in the container open, said tube having a length in the container equal to at least four-fifths of the length of the container and having at least seven orifices in the wall of said tube communicating the interior of said tube with the container, said orifices each being of a diameter equal to one-third of the internal diameter of said tube, each orifice being further from the adjacent orifice closer to the said one end of the container than from the adjacent orifice closer to the free end of the tube, the ratios of the spacings between said orifices being 15:10:7:5:3:2.
